SINKER HEAD FOR KNITTING MACHINES

Arthur J. Cobert, Chattanooga, Tenn., assignor
of one-half to Bryan E. F. Mills, Inc., Chat-
tanooga, Tenn., a corporation

Application November 4, 1950, Serial No. 194,110

9 Claims. (Cl. 66—110)

1

This invention relates to an improved sinker head for knitting machines, and more particularly to sinker heads of straight bar, full-fashioned hosiery machines; but the invention is also applicable to other types of knitting machines comprising slotted sinker heads for the accommodation of sliding sinkers or sinkers and dividers.

In such sinker heads as used most generally, the hard steel dividers and sinkers are accommodated in slots in the upper and lower parts of the head, and the sliding motion of the sinkers in these slots causes the comparatively soft metal of the sinker head to wear under contact with the upper and lower edges of the sinkers. The sinkers most frequently in action cause the greatest wear, and this unevenness in the wear results in a lack of uniformity in the operation of the sinkers and thus causes still further trouble, and it is necessary from time to time to replace the complete head or to recut the slots. This reslotting is a time consuming, troublesome and costly proceeding, and after the heads are reslotted once or twice they must be jacked.

More recently it has been suggested to provide the sinker head with hard metal wear bars to guide the sinkers in the slots, as shown in Patent No. 2,061,299, which was granted November 17, 1936 to my father, the late Joseph K. Cobert. My invention is essentially an improvement in the construction shown in that patent.

An object of my invention is to provide a sinker head having wear bars arranged to provide bearing surfaces for the sinkers without undue tolerance.

Another object of my invention is to provide a sinker head in which tolerance for the sinkers is quickly and easily adjustable.

Another object of my invention is to provide a sinker head in which the necessity for stiffening screws is obviated.

Another object of my invention is to provide a sinker head which can be manufactured without being purposely bowed.

Another object is to provide a sinker head in which the sinkers are mounted between wear bars and clearance is provided between the sinkers and the cover part of the head.

Another object of my invention is to provide a sinker head which is simple and easy to manufacture, rugged and durable in use, and accurate and efficient in operation.

Other and further objects and advantages of my invention will be apparent from the following description taken in conjunction with the accompanying drawing in which like characters of

2

reference designate corresponding parts throughout the several views, and wherein:

Fig. 1 is a cross-sectional end view of a sinker head embodying my invention, and showing a sinker and divider in place therein.

Fig. 2 is a fragmentary perspective view of the sinker head shown in Fig. 1, with the sinkers and dividers removed.

Fig. 3 is a cross-sectional end view showing a detail.

Fig. 4 is a cross-sectional view taken along the line 4—4 in Fig. 1.

In the embodiment chosen for purpose of illustration, the sinker head comprises a base 10 and a cover 11, provided respectively with transverse slots 12, 13, within which the sinkers 14 and dividers 15 are accommodated for sliding movement as is well understood.

The upper face of the base 10 is provided with spaced longitudinal grooves 16, 16' within which the lower wear bars 17, 17', respectively, are placed. The wear bars 17, 17' are held firmly in place by screws 18, 18' which extend upwardly through the base 10 and have their heads recessed in the lower face thereof. The wear bars 17, 17' are made of steel or other wear resistant material.

The cover 11 is provided with spaced longitudinal slots 19, 19' which extend vertically through the cover and within which the wear bars 20, 20', respectively, are adjustably held by the screws 21, 21', respectively, which extend inwardly from the sides of the cover and have their heads recessed therein. Each of the wear bars 20, 20' is slotted, as best seen in Fig. 4, to permit the screws 21, 21' to pass therethrough and to afford vertical adjustment of the wear bars 20, 20' to provide and maintain proper tolerance for the transverse sliding movement of the sinkers and dividers.

A verge plate 22, against which the sinkers are pressed by the slur cam (not shown), is attached to the head 11 in the customary manner, as by bolts 23 (only one being shown).

A sinker head is usually 14 to 15 inches in length between the first and last sinkers, and workers in the prior art have found it very difficult to fabricate the base and cover without some bow or curve in one of the sections. This is particularly true of the cover since it is usually thinner than the base. When the cover does not follow a true straight line throughout its length, it is impossible to maintain uniform clearance between all of the sinkers and the head.

For example, if the cover should bow downwardly

at its center, then the center sinkers would be too tight, while the sinkers at the ends would be too loose. In order to overcome this difficulty, it has been common practice to place stiffening screws between the cover and the base about one-third the distance from each end. This presents a very difficult and complicated problem in manufacture. For example, in the case of a sixty gauge sinker head, the sinkers and dividers are spaced on .025" centers. These sinkers and dividers are .005" in thickness, which leaves a clearance of .020" between adjacent sinkers and dividers. In this clearance must be placed the stiffening screw. This is accomplished by machining the screw down to approximately .018" at its center portion and inserting it in the head before the sinkers are inserted. The screw must have a square shoulder at top and bottom, and the holes in the head must also be square to prevent the screw from turning while it is being tightened in the head. In order to be of any effect at all, this screw must be tightened against an outward bow of the cover, rather than an inward bow, to draw the parts of the head together. For this reason, prior art sinker heads have been made with an exaggerated outward bow in the cover so that the stiffening screws will have some effect.

In my improved sinker head, stiffening screws are entirely eliminated. In the first place, my cover is made substantially heavier than normal, in order to receive the inserts, or wear bars. Then, if there is any bow in the head to start with, it will have no effect upon the finished product, because I do not depend upon the cover for the sinker clearance. My inserts are made in true line, hardened and ground this way, and then dropped into the slots in the cover. The straight line edge of the inserts bears against the sinkers, while the cover is spaced from them. In fact, I allow a clearance of .012" between the top of the sinker and the cover, this being more than sufficient to take care of any bow in the head. Thus I eliminate manufacturing problems and obtain a greater degree of accuracy in the sinker tolerance to provide a more smoothly operating piece of machinery which will produce a more uniform and desirable product.

By providing hardened steel inserts, instead of having the sinkers ride in and on a long groove of brass, from which the sinker heads are usually fabricated, these inserts act as bearings, reducing the frictional resistance when the sinkers are retracted or moved forward by the slur cam. But the three-point suspension of the prior art as found in Patent No. 2,061,299, could not be satisfactorily accomplished without undue tolerance. A three-point suspension is fine for clamping an object between surfaces; but, where the sinker must slide freely without undue tolerance, my construction is a great improvement. It will be noted that I provide a pair of fixed inserts 17, 17' in the base, and a pair of vertically adjustable inserts 28, 28' in the cover; and it will be seen that the inserts in the cover are over and above the inserts in the base so that no three-point clamping effect is had in my construction, although the inserts in the cover are separately adjustable and therefore afford easy adjustment for minimum clearance for the sinkers. The inserts in the base, lying beneath the inserts in the cover, need not be adjustable; but, if any of the inserts become worn on a face, they can be easily taken out and turned over to use the opposite face.

Having thus described my invention, it will be obvious to those skilled in the art that many modifications and changes can be made in the embodiment illustrated without departing from the scope of my invention as defined in the appended claims.

I claim:

1. In a sinker head for knitting machines, a base, a cover on said base, said base and said cover being transversely slotted to slidably receive a plurality of sinkers therebetween, said base being provided with a plurality of wear bars to bear against said sinkers, said wear bars extending slightly beyond the bottom of the transverse slots in said base, said cover being provided with a plurality of wear bars, said last mentioned wear bars being adjustably fixed to said cover, said last mentioned wear bars being adjustable to extend a desired distance beyond the bottom of the transverse slots in said cover, said wear bars on said base and said wear bars on said cover being arranged in pairs with each wear bar on said cover opposite a wear bar on said base.
2. In a sinker head for knitting machines, a base, a cover on said base, said base and said cover being transversely slotted to slidably receive a plurality of sinkers therebetween, said base being provided in its face adjoining said cover with a plurality of longitudinal grooves, wear bars in said grooves, said cover being provided with a plurality of longitudinal slots extending inwardly from the face of said cover adjoining said base, and wear bars removably positioned in said slots in said cover, said last mentioned wear bars being adjustably held in said longitudinal slots in said cover and being adjustable to extend a desired distance beyond the bottom of the transverse slots in said cover, said wear bars in said base and said wear bars in said cover being arranged in pairs with each wear bar in said cover opposite a wear bar in said base.
3. In a sinker head for knitting machines, a base, a cover on said base, said base and said cover being transversely slotted to slidably receive a plurality of sinkers therebetween, said base being provided in its face adjoining said cover with a plurality of longitudinal grooves, wear bars in said grooves, said wear bars being removably fixed in said grooves, said wear bars extending slightly beyond the bottom of the transverse slots in said base, said cover being provided with a plurality of longitudinal slots extending inwardly from the face of said cover adjoining said base, and wear bars removably positioned in said slots in said cover, said last mentioned wear bars being adjustably held in said longitudinal slots in said cover, said last mentioned wear bars being adjustable to extend a desired distance beyond the bottom of the transverse slots in said cover, said wear bars in said base and said wear bars in said cover being arranged in pairs with each wear bar in said cover opposite a wear bar in said base.
4. In a sinker head for knitting machines, a base, a cover on said base, said base and said cover being transversely slotted to slidably receive a plurality of sinkers therebetween, said base being provided in its face adjoining said cover with a plurality of longitudinal grooves, wear bars in said grooves, said wear bars being removably fixed in said grooves, said wear bars extending slightly beyond the bottom of the transverse slots in said base, said cover being provided with a plurality of longitudinal slots extending inwardly from the face of said cover ad-

joining said base, and wear bars removably positioned in said slots in said cover, said last mentioned wear bars being adjustably held in said longitudinal slots in said cover, said last mentioned wear bars being individually adjustable to extend a desired distance beyond the bottom of the transverse slots in said cover, said wear bars in said base and said wear bars in said cover being arranged in pairs with each wear bar in said cover opposite a wear bar in said base.

5. In a sinker head for knitting machines, a base, a cover on said base, said base and said cover being transversely slotted to slidably receive a plurality of sinkers therebetween, said base being provided in its face adjoining said cover with a plurality of longitudinal grooves, wear bars in said grooves, said wear bars being removably fixed in said grooves, said wear bars extending slightly beyond the bottom of the transverse slots in said base, said cover being provided with a plurality of longitudinal slots extending through said cover from the face thereof adjoining said base to the opposite face, and wear bars removably positioned in said slots in said cover, said last mentioned wear bars being adjustably held in said longitudinal slots in said cover, said last mentioned wear bars being adjustable to extend a desired distance beyond the bottom of the transverse slots in said cover, said wear bars in said base and said wear bars in said cover being arranged in pairs with each wear bar in said cover opposite a wear bar in said base.

6. In a sinker head for knitting machines, a base, a cover on said base, said base and said cover being transversely slotted to slidably receive a plurality of sinkers therebetween, said base being provided in its face adjoining said cover with a plurality of longitudinal grooves, wear bars in said grooves, said wear bars being removably fixed in said grooves, said wear bars extending slightly beyond the bottom of the transverse slots in said base, said cover being provided with a plurality of longitudinal slots extending through said cover from the face thereof adjoining said base to the opposite face, and wear bars removably positioned in said slots in said cover, said last mentioned wear bars being adjustably held in said longitudinal slots in said cover, said last mentioned wear bars being individually adjustable to extend a desired distance beyond the bottom of the transverse slots in said cover, said wear bars in said base and said wear bars in said cover being arranged in pairs with each wear bar in said cover opposite a wear bar in said base.

7. In a sinker head for knitting machines, a base, a cover on said base, said base and said cover being transversely slotted to slidably receive a plurality of sinkers therebetween, said base being provided in its face adjoining said cover with a plurality of longitudinal grooves, wear bars in said grooves, said wear bars being removably fixed in said grooves, said wear bar extending slightly beyond the bottom of the transverse slots in said base, said cover being provided with a plurality of longitudinal slots extending inwardly from the face of said cover adjoining said base, and wear bars removably positioned in said slots in said cover, said last mentioned wear bars being adjustably held in said longitudinal slots in said cover by fastening means extending inwardly from the sides of said cover, said last mentioned wear bars being slotted for cooperation with said fastening means so that said wear bars in said cover can be individually adjusted to extend a

desired distance beyond the bottom of the transverse slots in said cover, said wear bars in said base and said wear bars in said cover being arranged in pairs with each wear bar in said cover opposite a wear bar in said base.

8. In a sinker head for knitting machines, a base, a cover on said base, said base and said cover being transversely slotted to slidably receive a plurality of sinkers therebetween, said base being provided in its face adjoining said cover with a plurality of longitudinal grooves, wear bars in said grooves, said wear bars being removably fixed in said grooves, said wear bars extending slightly beyond the bottom of the transverse slots in said base, said cover being provided with a plurality of longitudinal slots extending through said cover from the face thereof adjoining said base to the opposite face, and wear bars removably positioned in said slots in said cover, said last mentioned wear bars being adjustably held in said longitudinal slots in said cover by fastening means extending inwardly from the sides of said cover, said last mentioned wear bars being slotted for cooperation with said fastening means so that said wear bars in said cover can be individually adjusted to extend a desired distance beyond the bottom of the transverse slots in said cover, said wear bars in said base and said wear bars in said cover being arranged in pairs with each wear bar in said cover opposite a wear bar in said base.

9. In a sinker head for knitting machines, a base, a cover on said base, said base and said cover being transversely slotted to slidably receive a plurality of sinkers therebetween, said base being provided in its face adjoining said cover with a plurality of longitudinal grooves, wear bars in said grooves, said wear bars being removably fixed in said grooves by means extending through said base from a face opposite said first mentioned face, said wear bars extending slightly beyond the bottom of the transverse slots in said base, said cover being provided with a plurality of longitudinal slots extending through said cover from the face thereof adjoining said base to the opposite face, and wear bars removably positioned in said slots in said cover, said last mentioned wear bars being adjustably held in said longitudinal slots in said cover by fastening means extending inwardly from the sides of said cover, said last mentioned wear bars being slotted for cooperation with said fastening means so that said wear bars in said cover can be individually adjusted to extend a desired distance beyond the bottom of the transverse slots in said cover, said wear bars in said base and said wear bars in said cover being arranged in pairs with each wear bar in said cover opposite a wear bar in said base.
